LIQUEFACTION AND RECTIFICATION
COLUMNArthur J. Fausek and Irving F. Fausek,
Clayton, Mo.

Application September 15, 1943, Serial No. 502,447

10 Claims. (Cl. 62—122)

1
This invention relates generally to liquefaction and rectification columns, and more specifically to such columns which are adapted for use in separating the constituents of atmosphere and my invention includes pumping means for pumping from the column medium separated and isolated through operation of the column, the predominant object of the invention being to provide a column of the type referred to above which includes improved means for automatically regulating and controlling the operation of the pumping means during operation of the column.

Fig. 1 is a diagrammatical view illustrating the present invention with the electrical portion thereof exaggerated for purposes of illustration.

Fig. 2 is a diagrammatical view illustrating certain electrical elements and wiring which constitute parts of the means of the present invention for automatically regulating and controlling the operation of the pumping means that forms part of the column illustrated in Fig. 1.

In the drawing, wherein is shown diagrammatically for purposes of illustration, merely, one embodiment of the invention, A designates a liquefaction and rectification column which is generally of conventional design. The column A comprises an elongated, vertically disposed housing B into the lower portion of which an air pipe C leads, said air pipe being shown in the drawing as adapted for delivering air under compression to a coil D that is disposed within the lower portion of the housing B. The column A includes within the housing thereof, a condenser E, having condensing tubes E', and disposed beneath said condenser is an annular receptacle F which receives from said condensing tubes of the condenser crude nitrogen resulting from operation of said condenser E. The column A includes within the housing B thereof groups of rectification trays G, H, J, and K which perform a well-known function. Likewise, arranged within the housing of the column A is a plurality of expansion valves L, M, and N, the expansion valve L being connected by a pipe L' to the nitrogen receptacle F, the expansion valve M being connected by a pipe M' to the bottom of the housing B of the column A, and the expansion valve N being connected by a pipe N' to the coil D.

The column A is provided with a pipe O, shaped as shown in Fig. 1, which communicates at its lower end with the interior of the housing B at the location of the lower portion of the condenser E, and at its upper end with the interior of said housing at the location of the upper portion of said condenser. Associated with the pipe O

2
is a pipe O' which is so related to said pipe O as to provide a liquid trap that maintains the level of the body of pure oxygen X that surrounds the tubes of the condenser E so that it may not fall below a predetermined level, and connected to said pipe O' is a suitable electrically operated pump P which pumps pure oxygen away from the column by way of the pipe P'. The column A includes, also, a conductor Q which communicates with the top of the column and conducts pure, gaseous nitrogen away from said column, said conductor Q having associated therewith a by-pass conductor R which leads from the conductor Q to the upper portion of a housing S that encloses the pipes O and O' and the pump P, there being a by-pass conductor T leading from the lower portion of said housing S back to the conductor Q. The conductor Q and the by-pass conductor R are provided, respectively, with valves Q' and R' which may be operated to cause gaseous nitrogen to flow uninterruptedly through the conductor Q, or to be by-passed through the housing S to pre-cool the pipes O and O' and the pump P.

The present invention includes means for automatically regulating actuation of the pump P, and this means comprises a vertically disposed tube I which is formed of glass or other suitable transparent material. Leading into the bottom 15 of the tube I and communicating with the interior thereof is a conductor 2, said conductor 2 at its opposite end being connected into the space within the housing B of the column A wherein the body X of pure liquid oxygen is contained. The conductor 2 is provided with an intermediate portion comprising parallel, upwardly extended conductor portions 2a and 2b connected at their upper ends by a curved conductor portion 2c, said upper, curved conductor portion 2c being ex- 20 tended slightly above the upper end of the tube I. Additionally, a second conductor 3 is provided which is connected, at one of its ends, into the upper end of the tube I, and at its opposite end, is connected into the housing B of the column 25 at a point slightly above the condenser E, said conductor 3 including a portion which is disposed slightly above the top of the tube I.

Because the conductor 2 is connected into the space of the interior of the housing B of the column A wherein the body of pure, liquid oxygen X is contained, liquid oxygen will fill the horizontal part of the conductor 2, located adjacent to the column A, and the vertical portion 2a of said conductor to a level in said vertical conductor portion 2a corresponding to the level of the body

of liquid oxygen X within the column A, as is indicated in Fig. 1. Also, a body of suitable liquid 4 is located in the tube 1 and in a portion of the conductor 2 which is disposed adjacent to the lower portion of the tube 1, and trapped within the conductor 2 between the body of liquid oxygen and the body of liquid 4 is a column of air, this column of air being located in the portion of the conductor 2 which is free from horizontal, liquid-indicating lines in Fig. 1.

From the foregoing it is plain that as the level of the body X of liquid oxygen within the column A raises or lowers, the level of the liquid oxygen in the vertical conductor portion 2a will raise and lower correspondingly therein, and as a consequence of such raising and lowering of the liquid oxygen level in the conductor portion 2a the level of the body of liquid 4 will raise and lower correspondingly within the tube 1, the column of air between the body of liquid oxygen in the conductor portion 2a and the body of liquid 4 serving as means for transmitting upward movement to the liquid within the tube 1 when the level of the liquid oxygen within the conductor portion 2a raises.

Associated with the tube 1 is a plurality of photo-electrical devices 5, 6, 7, and 8, which are spaced vertically with respect to said tube 1, as is shown diagrammatically in Fig. 1. In other words, at one side of the tube 1 the tubes of the photo-electrical devices are arranged, and at the opposite side of said tube 1 the light beam-projecting elements of the respective photo-electrical devices are arranged. As previously stated herein, the tube 1 is made of transparent material, but the body of liquid 4 therein is so characterized that the light beams of the photo-electrical devices will not pass therethrough, said body of liquid 4 being, for instance, water or other liquid, in which a suitable dye has been incorporated to render it opaque. As a result of this situation the presence of a part of the body of liquid 4 between the tube of any one of the photo-electrical devices and its associated light beam-projecting element, will interrupt the light beam, while the absence of a part of the body of liquid 4 between said tube and its associated light beam-projecting element will permit the light beam to pass through the tube 1 to the tube of the photo-electrical device.

The tubes of the photo-electrical devices 5, 6, 7, and 8, are connected by suitable electrical wiring 9 to the mechanism of an electrical relay 10, and said mechanism of said electrical relay is connected by suitable electrical wiring 11 to the operating means of the pump P (see Fig. 2). The electrical wiring 9 and 11 in cooperation with the mechanism of the relay 10 provide a separate electrical circuit for the tube of each photo-electrical device which leads to the pump P, and on energization of the circuits associated with the tubes of the photo-electrical devices 5, 6, and 7, by interruption of the light beam of said devices, the pump will be operated at different speeds, while energization of the circuit associated with the tube of the photo-electrical device 8 will, through cooperation of the relay 10, cause operation of the pump to be stopped.

From the foregoing it is obvious that when the body of liquid 4 within the tube 1 is at such level therein that the light beam of the uppermost photo-electrical device 5 is interrupted by said body of liquid, the pump will be operated at high speed. Likewise, it is plain that as the level of the liquid 4 moves downwardly in the tube 1, in response to lowering of the level of the body of

liquid oxygen X within the housing of the column A, the high speed operation of the pump P will be interrupted and the pump will be operated at intermediate speed, and then at low speed, if the level of the body of liquid within the tube 1 drops sufficiently low to permit the light beam of the photo-electrical device 7 to pass through the tube 1 to the tube of said device, the operation of the pump being stopped entirely if the level of the body of liquid within the tube 1 drops sufficiently to permit the light beam of the photo-electrical device 8 to pass through the tube 1 to the tube of said device. In like manner elevation of the level of the body of liquid X within the housing of the column A from a very low point will cause the pump P to be first operated at low speed, then at intermediate speed, and finally at high speed. Thus, the operation of the pump P is completely controlled at all times during operation of the column A in accordance with the level of the body of liquid X and in an automatic manner, so that at any and all times when the pump should be in operation it is operated at the proper speed to provide for the most efficient operation of the column, and so that the pump P is stopped when the level of the body of liquid oxygen X is so low that the pump should not be operated.

We claim:

1. In an apparatus for separating gas mixtures a liquefaction and rectification column having a housing in which is maintained a body of liquid whose level varies during operation of the column, an electrically operated pump connected to said housing for withdrawing liquid from said body of liquid, and means for automatically controlling operation of said pump in accordance with the level of said body of liquid, said pump-controlling means including a container formed of material through which light may pass, a plurality of spaced photo-electrical devices associated with said container with the tubes and the light beam projecting elements of said devices disposed at opposite sides of said container, said tubes of said photo-electrical devices being so connected electrically to said pump that flow of current through the tubes of different photo-electrical devices will cause the pump to be operated at different speeds, means movable longitudinally of said container for interrupting the light beams of the photo-electrical devices, and means for moving the last-mentioned means in accordance with the vertical movement of the level of said liquid within the housing of said column, said means which is movable longitudinally of said container being different in character from that of the body of liquid of said housing.

2. In an apparatus for separating gas mixtures a liquefaction and rectification column having a housing in which is maintained a body of liquid whose level varies during operation of the column, an electrically operated pump connected to said housing for withdrawing liquid from said body of liquid, and means for automatically controlling operation of said pump in accordance with the level of said body of liquid, said pump-controlling means including a container formed of material through which light may pass, a plurality of spaced photo-electrical devices associated with said container with the tubes and the light beam projecting elements of said devices disposed at opposite sides of said container, said tubes of said photo-electrical devices being so connected electrically to said pump that flow of current through the tubes of different photo-

electrical devices will cause the pump to be operated at different speeds, means comprising a body of liquid through which the light beams of said photo-electrical devices may not pass and which is movable longitudinally of said container for interrupting the light beams of the photo-electrical devices, and means for moving the last-mentioned means in accordance with the vertical movement of the level of said liquid within the housing of said column, said body of liquid which is movable longitudinally of said container being different in character from that of the body of liquid of said housing.

3. In an apparatus for separating gas mixtures a liquefaction and rectification column having a housing in which is maintained a body of liquid whose level varies during operation of the column, an electrically operated pump connected to said housing for withdrawing liquid from said body of liquid, and means for automatically controlling operation of said pump in accordance with the level of said body of liquid, said pump-controlling means including a container formed of material through which light may pass, a plurality of spaced photo-electrical devices associated with said container with the tubes and the light beam projecting elements of said devices disposed at opposite sides of said container, said tubes of said photo-electrical devices being so connected electrically to said pump that flow of current through the tubes of different photo-electrical devices will cause the pump to be operated at different speeds and to cause operation of said pump to be interrupted, means comprising a body of liquid through which the light beams of said photo-electrical devices may not pass and which is movable longitudinally of said container, and means for moving the last-mentioned body of liquid in accordance with vertical movement of the level of said body of liquid within the housing of the column for interrupting the light beams of the photo-electrical devices, said container and the portion of the housing of the column in which the body of liquid of the column is contained being connected by a conductor in which parts of the body of liquid of the column and the body of liquid of the container are disposed, and a trapped medium interposed between said liquid body parts in said conductor.

4. A liquefaction and rectification column having a housing in which is maintained a body of liquid whose level varies during operation of the column, an electrically operated pump connected to said housing for withdrawing liquid from said body of liquid, and means for automatically controlling operation of said pump in accordance with the level of said body of liquid, said pump-controlling means including a container formed of material through which light may pass, a plurality of spaced photo-electrical devices associated with said container with the tubes and the light beam projecting elements of said devices disposed at opposite sides of said container, said tubes of said photo-electrical devices being so connected electrically to said pump that flow of current through the tubes of different photo-electrical devices will cause the pump to be operated at different speeds, means comprising a body of liquid through which the light beams of said photo-electrical devices may not pass and which is movable longitudinally of said container, and means for moving the last-mentioned body of liquid in accordance with vertical movement of the level of said body of liquid within the housing of the column for interrupting the light beams of the

photo-electrical devices, said container and the portion of the housing of the column in which the body of liquid of the column is contained being connected by a conductor in which parts of the body of liquid of the column and the body of liquid of the container are disposed, and a trapped body of air interposed between said liquid body parts in said conductor.

5. A liquefaction and rectification column having a housing in which is maintained a body of liquid oxygen whose level varies during operation of the column, a pump connected to said housing for withdrawing liquid from said body of liquid oxygen, a conductor communicating with the top of the housing of said column through which gaseous nitrogen passes from the column, a receptacle surrounding said pump, by-pass conducting means for by-passing gaseous nitrogen from said conductor through said receptacle for pre-cooling said pump, and means for controlling operation of said pump.

6. A liquefaction and rectification column having a housing in which is maintained a body of liquid oxygen whose level varies during operation of the column, a pump connected to said housing for withdrawing liquid from said body of liquid oxygen, a conductor communicating with the top of the housing of said column through which gaseous nitrogen passes from the column, a receptacle surrounding said pump, by-pass conducting means for by-passing gaseous nitrogen from said conductor through said receptacle for pre-cooling said pump, and means for controlling operation of said pump automatically in accordance with the level of said body of liquid oxygen within the housing of the column.

7. A liquefaction and rectification column having a housing in which is maintained a body of liquid oxygen whose level varies during operation of the column, a pump connected to said housing for withdrawing liquid from said body of liquid oxygen, a conductor communicating with the top of the housing of said column through which gaseous nitrogen passes from the column, a receptacle surrounding said pump, by-pass conducting means for by-passing gaseous nitrogen from said conductor through said receptacle for pre-cooling said pump, and means including photo-electrical means for controlling operation of said pump automatically in accordance with the level of said body of liquid oxygen within the housing of the column.

8. In an apparatus for separating gas mixtures a liquefaction and rectification column having a housing in which is maintained a body of liquid whose level varies during operation of the column, an electrically operated pump connected to said housing for withdrawing liquid from said body of liquid, and means for automatically controlling operation of said pump in accordance with the level of said body of liquid, said pump-controlling means including a container formed of material through which light may pass, a plurality of spaced photo-electrical devices associated with said container with the tubes and the light beam projecting elements of said devices disposed at opposite sides of the container, said tubes of said photo-electrical devices being so connected electrically to said pump that flow of current through the tubes of different photo-electrical devices will cause the pump to be operated at different speeds, means comprising a body of liquid through which the light beams of said photo-electrical devices may not pass and which is movable longitudinally of said container, and means for moving the last-mentioned body of liquid in accordance with vertical movement of the level of said body of liquid within the housing of the column for interrupting the light beams of the

75 which is movable longitudinally of said container,

and means for moving the last-mentioned body of liquid in accordance with vertical movement of the level of said body of liquid within the housing of the column for interrupting the light beams of the photo-electrical devices, said container and the portion of the housing of the column in which the body of liquid of the column is contained being connected by a conductor in which parts of the body of liquid of the column and the body of liquid of the container are disposed.

9. In an apparatus for separating gas mixtures, a liquefaction and rectification column having a housing in which is maintained a body of liquid whose level varies during operation of the column, an electrically operated pump connected to said housing for withdrawing liquid from said body of liquid within said housing of said column, and means for automatically controlling operation of said pump in accordance with the level of said body of liquid within the housing of said column, said controlling means including a container, means movable upwardly and downwardly within said container, means for moving the last-mentioned means in accordance with vertical movement of the level of said liquid within the housing of the column, and electrical means including a plurality of controlling elements adapted to be respectively rendered effective at different vertical positions of said means within said container so as to deliver electrical energy to said electrically operated pump for causing said electrically operated pump to be operated at different speeds depending on the level of said body of liquid within the housing of said column, said means which raises and lowers within said container being different in character from that of said body of liquid within the housing of said column.

10. In an apparatus for separating gas mixtures, a liquefaction and rectification column having a housing in which is maintained a body of liquid whose level varies during operation of the column, an electrically operated pump connected

to said housing for withdrawing liquid from said body of liquid within said housing of said column, and means for automatically controlling operation of said pump in accordance with the level of said body of liquid within the housing of said column, said controlling means including a container, a body of liquid movable upwardly and downwardly within said container, means for moving said body of liquid within said container in accordance with the vertical movement of the level of said liquid within the housing of the column, and electrical means including a plurality of controlling elements adapted to be respectively rendered effective at different vertical positions of said body of liquid within said container so as to deliver electrical energy to said electrically operated pump for causing said electrically operated pump to be operated at different speeds depending on the level of said body of liquid within the housing of said column, said body of liquid which raises and lowers within said container being different in character from that of said body of liquid within the housing of said column.
